CROSSING GATE LOCK

Morris McD. Dilley, Louisville, Ky., assignor to
Associated Manufacturers' Agency, Inc., Louis-
ville, Ky.

Application November 25, 1938, Serial No. 242,195

5 Claims. (Cl. 39—8)

This invention relates to means for retaining a traffic crossing gate positively in either its operated or inoperative positions, these positions being hereinafter referred to as a lowered or horizontal position and a clear or up position. An important object of the invention is to provide means which will permit the gate to travel on to the desired selected position, but after reaching that position, will prevent its return until the return action is indicated. In the form herein shown, the invention is applied to a light duty type power gate which may be applied to new or existing warning sign poles or the like, although the invention is equally as well adapted for use in heavy duty type gates of other constructions.

A further feature of the invention is that upon power failure the automatic holding means may be released to permit the gate arm to assume either the clear or down positions depending upon the arrangement of counterweights so as to meet the requirements of the particular installation as to whether or not the crossing is to be kept clear or closed in the event of such power failure.

These and many other objects and advantages of the invention will become apparent to those versed in the art in the following description of the one particular form of the invention as illustrated more or less diagrammatically in the accompanying drawings, in which—

Fig. 1 is a front elevation of a crossing gate embodying the invention;

Fig. 2, a detail on enlarged scale in side elevation of a gate actuating mechanism;

Fig. 3, a detail in vertical section on the line 3—3 in Fig. 2;

Fig. 4, a top plan view on a still further enlarged scale of the automatic holding valve;

Fig. 5, an end elevation on a reduced scale;

Fig. 6, a central vertical section on the line 6—6 in Fig. 5;

Fig. 7, a vertical section on the line 7—7 in Fig. 5 on enlarged scale;

Fig. 8, a central longitudinal vertical section through the valve similar to that shown in Fig. 6 but having a modified form of release; and

Fig. 9, a schematic wiring diagram.

Like characters of reference indicate like parts throughout the several views in the drawings.

In the present form of the invention, the entire control is carried within a box 10 which may be mounted on the ordinary signal post 11 customarily employed at a highway crossing over a railway. The invention may be employed cus-

tomarily (although not necessarily so) with the usual flasher lamps 12a and 12b together with the usual visual warnings as to "Railroad crossing" and "Stop on red signal."

5 The box 10 is adjustably mounted on the post 11 by means of bolts 12 extending through knockouts in the box. This permits adjusting the control box 10 at any elevation or angular position around the post 11 as may be desired or required for the particular crossing.

A single arm 13 is carried by a yoke 14 which hangs downwardly from a transverse axle 15 extending through the box 10. The yoke 14 is so formed as to have its mass suspended below

15 the axle 15. The yoke 14 curves around upwardly to carry weights 16 normally above the level of the arm 13 when the arm is in the lowered position. The travel of the gate is indicated in Fig. 1 from the dash lines of the up or clear position down to

20 the solid lines for the closed or lowered position. This peculiar mounting of the arm 13 not only gives an easier control of the movement of the arm 13 but also provides clearance for the various signals on the post 11 when the arm is in the up position.

The axle 15 carries a gear segment 17 which meshes with a vertically disposed rack 18 directly connected to a piston rod 19 carried by a cylinder 20 to travel vertically. The cylinder 20 carries a piston 21, Fig. 3, to which the rod 19 is connected. The cylinder 20 is closed at both ends. The gate is actuated by travel of the piston 21 within the cylinder 20 by pumping oil into the cylinder to shift the piston accordingly.

35 To supply the oil under pressure, a pump 22, generally of the gear type, in any event being of a rotary construction, is driven by an electric motor 23, here shown as in direct connection through the shaft 24. Between the pump 22 and the cylinder 20 is located the locking valve 25.

This valve has a major horizontally disposed cylinder 26 within which are mounted a pair of pistons 27 and 28 in spaced apart relation on a common piston rod 29. The pistons 27 and 28 in the present form consist each of a pair of oppositely disposed leather cups. There is no external extension of the rod 29 from the cylinder 26 and the movement of the pistons is created solely by variations of pressure on their faces. A longitudinal passageway 30 extends along one side of the valve 25 to have end passageways 31 and 32 respectively continue from the passageway 30 across the ends of the valve and discharge into the respective ends of the cylinder 26. This passageway 30 is intercepted by a pair of spaced

45 50 55

apart ball check valves 33 and 34 respectively so that fluid flow through the passageway from either end of the cylinder 26 is arrested selectively by these valves. That part of the passageway 30 which lies between the two valves 33 and 34 has a transverse passageway 35 leading therefrom to discharge into the cylinder 26 through the opening 36.

The pump 22 has a discharge pipe 37 leading to the valve 25 and discharging into the passageway 32 through the nipple 38, Fig. 7. Assuming that the gate arm 13 is to be lowered and the motor 23 is in operation and driving the pump 22, oil will be forced through the pipe 37 into the passageway 32. The only escape from that passageway by reason of the presence of the check valve 34 is through the opening into the end of the cylinder 26, Fig. 6. The oil flowing into the cylinder 26 will push the piston 28 back in the cylinder to its limit of travel which is reached when the piston 27 strikes the opposite cylinder end, as indicated in Fig. 6. The cylinder 26 is provided with one or more openings 39 through the cylinder wall ahead of the piston 28 so that the oil may escape from the cylinder as it is pumped therein into an upper passageway 40 from which a pipe 41 leads to the top of the cylinder 20. Thus the oil is carried from the pump 22 through the valve cylinder 26 and into the top of the cylinder 20 to force the piston 21 downwardly and thus lower the gate 13.

While this down travel of the piston 21 has been taking place, the oil in the lower part of the cylinder 20 under the piston 21 is forced outwardly through the pipe 42 leading from the bottom of the cylinder and connecting with the passageway 43 at the top of the valve 25. This passageway 43 opens into the cylinder 26 between the pistons 27 and 28 through one or more openings 44. The oil entering the cylinder 26 from these openings 44 flows between the pistons 27 and 28 and leaves the cylinder 26 through the opening 36 which is never covered by either piston. This discharging oil comes into the central part of the passageway 30 between the check valves 33 and 34. Since the pump is supplying pressure in that part of the passageway 30 which connects with the passageway 32, the valve 34 will remain seated, but the valve 33 may lift and allow the discharge oil to flow therewith into the other part of the passageway 30 and leave that passageway through the opening 45 from which the pipe 46 leads back to the pump 22 to constitute the intake of the pump in this sequence of operations. In other words, there is a closed circuit of the oil which is used as the medium for supplying pressure to shift the piston 21.

When the piston 21 reaches its lower limit of travel, which is that position wherein the gate arm 13 is horizontally disposed, a lower limit switch 47, Fig. 2, will be opened by any suitable means such as a finger 48 on the rack 18 and thereby open the electrical circuit which includes the motor 23 and thus stop the pump 22. When the pump has stopped, there is a residual pressure left in the cylinder 20 on the upper side of the piston 21 and this pressure is maintained by reason of the fact that there can be no back flow of oil through the valve 25 by reason of the presence of the check valve 34 as will be readily apparent in following the connections from the cylinder to the pump. It is to be kept in mind that the only discharge permissible from the cylinder 20 with either direction of travel of the piston 21 is through the opening 36 in the cyl-

inder 26, and further that once pressure is applied to the cylinder, that pressure cannot be relieved until the pistons 27, 28 have been shifted to the opposite end of the cylinder 26 so as to 5 interconnect that pressure side of the cylinder with the outlet opening 36.

Thus it is to be seen that by interposing this control valve 25 between the pump and the cylinder, a piston check is introduced to maintain the pressure in the cylinder irrespective of pump leakage or the like. The gate cannot be pushed upwardly without release of this pressure. To 10 permit adjustment of the gate or checking of it, there is interposed a by-pass between the passageways 40 and 43 intercepted by the valve 50, Fig. 6, which in this form is manually operated. By opening the valve 50 through the external handle 51, there is a direct interconnection made 15 between the passageways 40 and 43 which relieves the pressure in the cylinder while allowing the oil to flow from the pressure side from the passageway 40 past the valve 50, through the passageway 43 and into the cylinder 26 and out through the opening 36.

This control of the by-pass between the passageways 40 and 43 may be electrically operated by means of a solenoid 52 normally included in the operating circuit to hold a valve 53 in a closed position, Fig. 8. The valve in this case would be 20 so constructed as to normally open by any such means as a spring 54 when the current fails so as to permit the gate arm 13 to swing to either an up or a down position depending upon the amount of weights 16 applied to the yoke 14. That is, where the arm 13 is not balanced by 25 weights 16, the gate 13 would drop to a closed position upon current failure, but where the arm 13 is overbalanced by the weights 16, it would lift to its open or up position upon current failure.

One sequence of operations has been described above. In order to lift the gate, regardless of whether the weights 16 fully balance or not the arm 13, the motor 23 is reversed in direction of 30 travel so as to reverse the direction of output of oil from the pump 22. In this case, the discharge from the pump 22 would be through the pipe 46 into the passageway 31 so as to initially drive the pistons 27 and 28 toward the opposite end of the cylinder 26 and thereby provide a path for the oil to flow from the passageway 31 to the openings 44 and out through the pipe 42 into the bottom of the cylinder 20. At the same time the openings 39 are then between the pistons 27 and 28 so as to open up the discharge passage 35 for the oil to the opening 36 into the passageway 30 past the check valve 34 and back to the pump 22 through the pipe 37.

When the rack 18 reaches its upper limit of 35 travel, it will open the limit switch 55 and thereby interrupt the circuit to the motor 23. Preferably the motor 23 is not only wound to be reversible but is also wound to give a higher speed on the reverse travel than it has on the initial down travel of the gate. The electrical circuit is indicated by the diagram as shown in Fig. 9, wherein wires 60, 61 lead from any suitable source of operating current, generally ten volts, direct current. Across these wires would be connected the solenoid winding 52 which normally holds the valve 53 in the closed position. A track relay 62 40 upon being energized pulls the switch 63 into the closed position and current then flows through the lower limit switch 47 normally in the closed position, assuming that the gate is in its raised

position. From the closed switch 47, the current flows through the conductor 65, through the relay winding 66 and back through the conductor 67 to the wire 61. The relay 66 closes switches 68, 69 which interconnect the common conductor 70 leading from the wire 60 with the two motor leads 71 and 72. The motor 23 is constantly connected with the wire 61. The motor 23 then remains in the circuit until the limit switch 47 is opened by the rack 18.

When the train leaves a block protecting the crossing, the relay 62 is then operated in the usual manner (by track circuits not shown) to cause the switch 63 to then interconnect the wire 60 with the wire 64 leading to the upper limit switch 55 which is closed after the rack 18 starts on its down travel in the initial operation above described. From the switch 55 leads conductor 73 to the relay 74 which has a return wire 75 connected with the wire 61. The relay 74 will close the switches 76 and 77 to interconnect the wire 60 with the motor leads 72 and 78 to give the reversing action. The motor 23 remains in this reverse circuit until the switch 55 is opened by the rack 18 at its upper limit of travel. Thus the motor 23 is again stopped and remains in that condition until the track relay 62 is again operated to lower the gate as above described.

While I have herein shown and described my invention in the one particular form, it is obvious that structural details may be varied without departing from the spirit of the invention, particularly in the type of pump employed and the exact structural details of the control valve, and I, therefore, do not desire to be limited to that precise form beyond the limitations as may be imposed by the following claims.

I claim:

1. In a crossing gate control, the combination with an operating cylinder, a piston in the cylinder, a pump having a reversible intake and discharge flow for supplying fluid to the cylinder to actuate the piston, of an interlocking valve between the pump and the cylinder, said valve having a cylinder, a piston in the cylinder with a fluid receiving space between ends of the piston, a passageway leading from each end of the valve cylinder to the discharge and intake of said pump, a discharge passageway leading from a port in the valve cylinder located to be always in communication with said piston space, said discharge passageway connecting with each of said valve cylinder end passageways, a check valve between said discharge passageway and each of the other passageways arranged to prevent flow from those passageways into the discharge passageway and permitting reverse flow, a passageway leading from a port in the valve cylinder to one end zone of the operating cylinder, another passageway leading from another port in the valve cylinder to the other end zone of the operating cylinder, said last ports being located to have said valve piston by travel thereof alternately include one of those ports and said discharge port in said piston space to control flow in said piston space to control flow therebetween.

2. In a crossing gate control, the combination with an operating cylinder, a piston in the cylinder, a pump having a reversible intake and discharge flow for supplying fluid to the cylinder to actuate the piston, of an interlocking valve between the pump and the cylinder, said valve having a cylinder, a piston in the cylinder with a fluid receiving space between ends of the piston, a passageway leading from each end of the

valve cylinder to the discharge and intake of said pump, a discharge passageway leading from a port in the valve cylinder located to be always in communication with said piston space, said 5 discharge passageway connecting with each of said valve cylinder end passageways, a check valve between said discharge passageway and each of the other passageways arranged to prevent flow from those passageways into the discharge 10 passageway and permitting reverse flow, a passageway leading from a port in the valve cylinder to one end zone of the operating cylinder, another passageway leading from another port in the valve cylinder to the other end zone 15 of the operating cylinder, said last ports being located to have said valve piston by travel thereof alternately include one of those ports and said discharge port in said piston space to control flow therebetween, and a valve controlled by-pass between said passageways leading to the operating cylinder.

3. In a crossing gate control, the combination with an operating cylinder, a piston in the cylinder, a pump having a reversible intake and discharge flow for supplying fluid to the cylinder to actuate the piston, of an interlocking valve between the pump and the cylinder, said valve having a cylinder, a piston in the cylinder with a fluid receiving space between ends of the piston, 20 a passageway leading from each end of the valve cylinder to the discharge and intake of said pump, a discharge passageway leading from a port in the valve cylinder located to be always in communication with said piston space, said discharge 25 passageway connecting with each of said valve cylinder end passageways, a check valve between said discharge passageway and each of the other passageways arranged to prevent flow from those passageways into the discharge passageway and permitting reverse flow, a passageway leading from a port in the valve cylinder to one end zone of the operating cylinder, another passageway leading from another port in the valve cylinder to the other end zone 30 of the operating cylinder, said last ports being located to have said valve piston by travel thereof alternately include one of those ports and said discharge port in said piston space to control flow therebetween, and a valve controlled by-pass between said passageways leading to the operating cylinder.

4. In a crossing gate control, a cylinder, a gate operating piston in the cylinder, a pump for supplying fluid to the cylinder under pressure, said pump being reversible in action, a gate position maintenance valve between the cylinder and the pump interconnected with intake and discharge fluid conductors to said pump, fluid conductors leading from the valve to connect with opposite ends of the cylinder, a piston in the valve initially shiftable by fluid delivered from the pump, said shifting causing one of said cylinder conductors to be interconnected through the valve with the discharge conductor of the pump to cause shifting of the gate operating piston, and said valve piston shifting also setting up a flow connection between the other of said cylinder conductors to said pump intake conductor, said pump discharge and intake conductors having an interconnecting passageway with a port in said valve controlled by said valve piston for selective communication with either of said cylinder conductors, and a pair of spaced check valves in said passageway

arranged to have said port discharge therebetween.

5. A crossing gate lock valve consisting of a cylinder, a conductor interconnecting each end of the cylinder and an intermediate port in the cylinder, a valve in said conductor on each side of said port arranged to close upon pressure in the conductor and to open upon pressure therebetween communicated through said port, said cylinder having an additional port toward each end, a conductor having a pair of discharge ports between said additional ports, a valve intercept-

ing said last conductor between said discharge ports and said additional ports, and a piston in the cylinder having a recessed central portion always in communication with said intermediate port, said piston being proportioned to travel to selectively uncover one of said additional ports within said recess and to uncover the other of the additional ports outside of the piston, said first conductor having an inlet and an outlet port each between a valve in the conductor and the conductor connection cylinder end.

MORRIS McD. DILLEY.
